UNITED STATES PATENT OFFICE.

ELMER ENGER, OF PENO, SOUTH DAKOTA.

HAYRACK-SILL ADJUSTER.

Application filed April 3, 1923. Serial No. 629,847.

To all whom it may concern:

Be it known that I, ELMER ENGER, a citizen of the United States, residing at Peno, in the county of Hyde and State of South Dakota, have invented certain new and useful 5 Improvements in a Hayrack-Sill Adjuster, of which the following is a specification.

The present invention relates to a hay rack sill adjuster and has for its principal 10 object to provide a device for attaching the sills to a wagon bolster in fixed relation to the post of the bolster and so that the distance between the sills may be varied if desired and then fixed against accidental displacement.

Another important object of the invention is to provide a device of this nature which is simple and efficient in construction, reliable in operation, inexpensive to manufacture, durable, and well adapted to the 20 purpose for which it is designed.

With the above and numerous other objects in view as will appear as the description progresses, the invention resides in certain novel features of construction, and in the combination and arrangement of parts 25 as will be hereinafter more fully described and claimed.

For the purpose of illustrating my invention, I have shown in the accompanying drawing that form thereof which is at present preferred by me, since the same will give in practice satisfactory and reliable results, although it is to be understood that the various instrumentalities of 35 which my invention consists can be variously arranged and organized and that my invention is not limited to the precise arrangement and organization of these instrumentalities as herein shown and described.

In the drawing—

Figure 1 is an elevation of a wagon bolster showing hay rack sills in section thereon and my devices in proper position.

Figure 2 is a detail perspective view of 45 one of my devices attached to a bolster.

Figure 3 is a detail perspective view of the body of one clamp with a gripping member detached therefrom,

Figure 4 is a detail perspective view of 50 the body of the other clamp, and

Figure 5 is a detail perspective of a jaw used with the clamp.

Referring to the drawing in detail it 55 will be seen that the bolster 1 may be of conventional construction being provided

with the usual end post 2 rising therefrom. The hay rack sills 3 are disposed transversely of the wagon bolster 1 and are held in place by my appliance. There are two 60 of these appliances one for each sill 3. Each appliance includes a pair of clamps A and B. The clamp A consists of a body plate 5 having bolts 6 rising from its ends and a bar 7 rising from one edge of its mid 65 portion. This bar 7 is provided at its ends with the transversely extending lugs 8 and at its intermediate portion with the transversely extending lugs 9. The lugs 8 and 9 extend in the same direction and are adapted 70 to be disposed along the sides of the post 2. This bar 7 is also provided with a series of apertures 10. A pair of jaws 11 are adjustable on the body plate 5. Each jaw 11 includes a body 13 having a longitudinally 75 extending slot 14 for receiving one of the bolts 6. At one end of the body portion 13 a downward extension 15 is provided terminating in a series of offset teeth 16 extending substantially parallel with the body 80 13. At the other end of the body 13 there is disposed an apertured lip 17 rising at right angles from the body 13 and in an opposite direction from the extension 15. There are two jaws 11 on the body plate 5 85 and they are locked in place by the thumb nuts 18 engaged with the bolts 6. A bolt 19 passes through the apertured lips 17 which are disposed adjacent each other so that they may be drawn toward each other 90 by a thumb nut 20 on the bolt 19. The teeth 16 of the extensions 15 engage the sides of the bolster 1 as is illustrated to advantage in Figure 2.

The clamp B consists of a body plate 5' having bolts 6' rising from its ends and a bar 7' rising from one side of its intermediate portion and provided with a series of apertures 10'. Thus far this clamp is identical with the clamp A just described and includes the same jaw structure indicated generally at 11'. A sill engaging member 22 is constructed with a plate body having an elongated longitudinally extending slot 23 therein and an overhanging hook extension 24 terminating in a series of teeth 25 for engagement with the upper edge of a sill 3. This engaging member 22 is mounted on the bar 7' by means of a bolt 26 which passes through the upper aperture 10'. 110

A bracing member C is disposed between the bars 7 and 7' and may be adjusted in

- its length for drawing these bars together or forcing them away from each other as may be desired. This member C includes a pair of threaded rods 28, one of which passes through an aperture 10' of bar 7' and the other through an aperture 10 of bar 7 and a turn buckle 29 engages the adjacent portions of these rods 28 for adjusting the length of the member C.
- 10 It is thought that the construction and operation of the device will now be readily understood without a more detailed description. It will be seen that the device possesses a large variety of usages and of course the present usage has merely been given by way of example.

Having thus described my invention what I claim as new is:—

1. An appliance of the class described including a pair of clamps, a pair of bars, one rising from each clamp, engaging means on the bars, and adjustable bracing means disposed between the bars in the manner and for the purpose specified.
2. An appliance of the class described including a pair of clamps, a pair of bars, one rising from each clamp, lugs extending from the side edges of one bar, and an engageable member adjustable on the other bar and including a hooked extension having a toothed terminal, and bracing means between the bars.
3. An appliance of the class described including a pair of clamps, each clamp consisting of a body plate, a pair of jaws adjustable on the body plate, and a standard

rising from the intermediate portion of the body plate, engaging means on the standards and bracing means between the standards.

4. An appliance of the class described for holding hay rack sills upon wagon bolsters including a clamp consisting of a plate body, bolts rising from the ends of the plate body, jaws engaging said bolts, nuts engaging said bolts for holding said jaws in adjusted positions thereon, each jaw consisting of a slotted body having a depending extension at one end terminating in a plurality of offset teeth and an apertured extension at its other end rising therefrom, a bolt passing through the apertured extensions and a nut engaged with the bolt for drawing the apertured extensions toward each other, a standard rising from the body plate, an engaging member adjustable vertically on the standard and including a hooked extension terminating in a series of teeth.

5. An appliance of the class described including a clamp for engagement with a wagon bolster, a standard extending from the clamp and including a hay rack sill engaging member, and adjustable means for bracing the standard in relation to the post of the bolster.

In testimony whereof I affix my signature in presence of two witnesses.

ELMER ENGER.
